Primary Examiner — Raphael Barkai(74) *Attorney, Agent, or Firm* — Polster, Lieder, Woodruff & Lucchesi, LC(57) **CLAIM**

The ornamental design for foldable glasses, as shown.

DESCRIPTION

FIG. 1 is a top view of a first embodiment of the foldable glasses showing my new design;

FIG. 2 is a rear view thereof;

FIG. 3 is a bottom view thereof;

FIG. 4 is a right side view thereof;

FIG. 5 is a left side view thereof;

FIG. 6 is a front view thereof;

FIG. 7 is a front, left side and top perspective view thereof;

FIG. 8 is a front, left side and top perspective view thereof with the foldable glasses in a partially folded configuration;

FIG. 9 is a front, left side and top perspective view thereof with the foldable glasses in a completely folded configuration with a corresponding latching element;

FIG. 10 is a front, left side and top perspective view thereof with the foldable glasses in a completely folded configuration with the latching element engaged; and,

FIG. 11 is a rear, right side and top perspective view thereof.

1 Claim, 4 Drawing Sheets(56)
